Patented Apr. 15, 1913.

UNITED STATES PATENT OFFICE.

WILLIAM M. BASHLIN, OF GROVE CITY, PENNSYLVANIA.

PROCESS OF EXTRACTING ROSIN AND OTHER BY-PRODUCTS FROM WOOD.

1,059,261.

Specification of Letters Patent.

Patented Apr. 15, 1913.

Application filed November 10, 1911. Serial No. 659,634.

To all whom it may concern:

Be it known that I, WILLIAM M. BASHLIN, a citizen of the United States, residing at Grove City, in the county of Mercer and State of Pennsylvania, have invented new and useful Improvements in Processes of Extracting Rosin and other By-Products from Wood, of which the following is a specification.

- 10 This invention relates to a process of extracting rosin and other by-products from wood and consists essentially in applying a solvent embodying a mixture of refined turpentine and deodorized benzin to the wood bearing the rosin and other products and taking up the latter in solution, and then separating the rosin from the turpentine.
- 15 The invention further consists in applying a mixture of refined turpentine and deodorized benzin to rosin bearing wood and taking up the rosin in solution under the action of heat, separating the rosin from the turpentine, and then extracting the residual turpentine from the wood, and conserving 20 the wood as freed from rosin, turpentine and other by-products for use in making paper or other pulp.

In carrying out the process and as an intermediate step to render the extraction of 30 the rosin, turpentine and other products from the wood more effective, the vessel or digester in which the wood is deposited for treatment will have the air withdrawn therefrom or a vacuum established therein. This 35 vacuum is established in the digester or containing vessel after the latter has been charged with the wood reduced to small pieces and prior to turning on the heat or subjecting the charge to the action of heat 40 to provide for a more effective elimination of the rosin and turpentine by the dissolving action of the combined turpentine and deodorized benzin. The process may, however, be carried on in its most simple form 45 without resorting to the establishment of the vacuum in the digester and at times when the extraction or elimination of the turpentine, rosin and by-products may be effectively carried on by the action of the 50 solvent embodying refined turpentine and deodorized benzin heated within the digester to a desirable temperature.

The preferred form of apparatus for carrying out the process is shown in the accompanying drawing.

The numeral 5 designates the main body

of the digester or still surrounded by a heating jacket 6 to which steam may be admitted from a suitable source through a pipe 7 having a valve 8. The heating jacket 6 extends around the bottom of the body 5 and upwardly to a dome-like top 9 which is provided with a suitable inlet 10 for charging the digester and also with an outlet pipe 11 for carrying off the vaporized products 65 and delivering them to a condensing coil 12 disposed in a tank 13 as usual. The tank 13 has a valved outlet 14 connected to the bottom thereof, and the lower extremity of the coil 12 is projected through the lower 70 portion of the body of the tank 13 and terminates in an outlet cock 15 from which the condensed vaporized products may pass into a suitable receptacle. A pressure gage 16, a thermometer 17, and a liquid level gage 75 18 coöperate with the interior of the body 5 of the digester to respectively indicate the steam pressure temperature and level of the liquid within the said body, and the jacket 6 is also provided with a steam gage 19. 80 In the center of the bottom of the body 5 is an outlet 20 having a valve 21 that may be suitably operated from the exterior to open the same for the discharge of the wood from the digester after the turpentine, rosin 85 and by-products have been eliminated therefrom. To one side of the outlet 20 a valved outlet pipe 22 communicates with the bottom of the digester body for withdrawing 90 from the latter the turpentine, rosin and such by-products as may be eliminated from the wood together with residual benzin and turpentine used in the first instance as a solvent, the pipe 22 leading to or communicating 95 with any suitable form of separating apparatus. On the opposite side of the outlet 20 a valved steam pipe 23 communicates with the bottom of the body of the digester, said steam pipe receiving its supply of steam from the same source as the pipe 7 or from 100 any other steam generating means. A vacuum creating pipe 24 having a suitable valve 25 also communicates with the upper portion of the body 5 of the digester and may be connected to any suitable form of suction 105 pump or apparatus for establishing the desired vacuum in the body of the digester.

At a suitable point above the bottom of the body 5 of the digester is a supplemental dumping bottom 26 consisting of a foraminous or other analogous open structure disk 110 which normally divides the digester into an

upper charge receiving chamber and a lower product receiving chamber, the said dumping bottom being pivoted as at 27 to turn and having at an opposite point a stem or rod 28 extending through the jacket 6 and terminating in an outer handle 29. Co-operating with the rod 28 exteriorly of the jacket 6 is a pawl and ratchet locking mechanism 30 which operates to maintain the dumping bottom 26 in true horizontal position particularly when the weight of the charge of wood is imposed thereon. Supported within the body 5 above the bottom 26 by means of suitable braces or spiders 31 is a distributor consisting of a vertical pipe 32 closed at its upper end and having a plurality of perforated tubular arms 33 extending outwardly therefrom in staggered relation. To the lower extremity of the pipe 32 a steam feed or supply pipe 34 is attached and provided with a valve 35, the pipe 34 being connected to a suitable steam source which may be the same source as that which supplies the pipes 7 and 23 or any other steam generating medium. In the upper central portion of the top 9 an admission pipe 36 for the solvent is connected and provided with a controlling valve 37.

In preparing the apparatus or digester for carrying out the process the valves 8, 25 and 35, and the valves in the pipes 20, 22 and 23 are closed and the inlet 10 is opened. A charge of resin bearing wood in comminuted condition, such as chips, is then introduced into the body 5 and falls onto the dumping bottom 6 and also in and around the different parts of the distributor embodying the pipe 32 and arms 33. A mixture of refined turpentine and deodorized benzin is then poured into the body over the charge of wood in such quantity as best adapted for carrying out the process, the proportions of the mixture of turpentine and deodorized benzin being found by practice to best serve the purpose to be three parts of turpentine and five parts of benzin, or about in the proportion of one-fifth turpentine and four-fifths benzin, the benzin preferably having fifty-eight to sixty specific gravity. It has also been found that the process is much more effective if the chips or comminuted wood are flooded with the mixture of turpentine and benzin. The inlet 10 is then closed and a vacuum is established in the digester by opening the valve 25 in the pipe 24 through the medium of the vacuum creating apparatus or device to which the said pipe is attached and subsequently the valve 25 is closed and steam permitted to enter and fill the jacket 6 by opening the valve 8 of the pipe 7 and at the same time the valve in the vapor outlet pipe 11 is opened. The digester is subjected to this heating operation for a sufficient length of time as may be found by practice in treat-

ing different kinds of resinous bearing wood or until all of the resin and by-products as well as the turpentine have been eliminated from the wood. The vapors pass off through the pipe 11, it being understood that this pipe is not opened until some time after the steam is admitted to the jacket 6, and the vapors thus liberated are condensed in the coil 12 and pass off into a suitable receptacle. In the first part of the operation, however, the pipe 11 may remain closed and all of the heavier products or those of a non-volatile character will pass through the supplemental bottom 26 and deposit in the bottom portion of the digester including the turpentine and deodorized benzin that may remain in the digester, and all of the material including the rosin held within the digester after the steps of the process thus far explained have been completed may be drawn off through the pipe 22 and conveyed to a suitable separating apparatus to recover the turpentine and portion of the benzin carried thereby as well as the rosin and other by-products. The turpentine and benzin recovered by the separating operation may be again used for a similar elimination or returned to the digester after the one charge has been completely treated and withdrawn. In some operations the digester may be effectively used with the same solvent mixture without establishing a vacuum, and under such conditions the valve 25 of the pipe 24 will remain closed and the valve in the pipe 11 may be immediately opened when steam is admitted to the jacket 6 so that the vapors produced may be quickly carried off and condensed and their constituents recovered by any of the well known means. After the charge of wood has been treated to eliminate the rosin and other by-products and together with the solvent withdrawn from the digester, steam under pressure is admitted through the pipe 23 and passes up through the charge of wood remaining in the digester to carry off all of the solvent mixture that may be still clinging to the wood and this mixture together with the steam passes off in the form of vapor through the pipe 11 and is condensed and subsequently separated, and under this treatment the wood will be entirely freed of any of the products that can be eliminated by the process explained and is then dumped into the bottom of the digester by turning the bottom 26, and from the bottom of the digester the wood may be withdrawn through the outlet 20 by opening the valve 21 and delivered to any other suitable treating apparatus or into a pit for the purpose of reducing the same to pulp by any of the well known alkaline methods.

The process as thus far described may be carried on effectively without the coöpera-

tion of any other instrumentality, but it is preferred that the distributor be utilized to render the elimination of the rosin and other products in the wood more positive and certain and above all to quicken the operation, and therefore during the time that the wood and solvent as hereinbefore specified are subjected to heat from the jacket 6, steam is admitted through pipe 34 by opening the valve 35 to the pipe 32 and arms 33, and from the latter passes out through all parts of the charge of wood and heats the latter and the solvent internally while the jacket is heating the wood and solvent externally, and thereby a more rapid elimination of the products from the wood is effected. When the distributor is used in the first treatment of the wood with the solvent it may be shut off when the second treatment by steam through the pipe 23 is pursued subsequent to withdrawal of the turpentine and remaining benzin and eliminated products, or if desired the distributor may be used to blow steam through the wood in conjunction with the steam entering through said pipe 23 and thereby carry off all the turpentine and other matter remaining in association with the wood that may be vaporized through the pipe 11 into the condenser 12.

30 The solvent hereinbefore described and embodying refined turpentine and deodorized benzin as its constituents, gives a result which is more advantageous than if the solvent consisted of either of the constituents alone, for the reason that the benzin is more penetrative and is a more quickly acting extractant than turpentine, especially in dissolving and eliminating the rosin, and the turpentine more perfectly acts to eliminate the turpentine of the wood or material treated by reason of the fact that it is refined and has a greater affinity for the like product in the wood for which it is used to eliminate. In other words, the turpentine will more quickly remove the turpentine from the wood or other material, while the deodorized benzin as above noted co-operates with the rosin.

35 In view of the difference in specific gravities of the refined turpentine and deodorized benzin the benzin in the first vaporization, due to its higher volatile characteristics, will issue from the still carrying very little of the turpentine vapor and may be recovered for further use at a comparatively reduced expense and in less time than if mixed with a large quantity of turpentine for reuse as a part of the solvent. Furthermore, it will be observed that deodorized benzin is used in contradistinction to ordinary benzin having a pungent odor and the advantage in this particular use is that the eliminated products or the turpentine and rosin are not affected, to any appreciable extent, by a benzin odor. Where gasolene

is used as a solvent, the rosin eliminated as well as the turpentine is materially affected by the objectionable odor of the gasolene and it is practically impossible to rid the rosin of such odor, and hence rosin so affected has a materially reduced commercial value. Another factor of importance in favor of the use of deodorized benzin is that explosions within the still are less liable to occur, whereas by the use of gasolene the danger of explosion in the still is always present. Therefore the combination of turpentine and deodorized benzin in the solvent gives a quicker or more expeditious elimination of the product sought from the material treated without any deleterious effect on the said product and requiring less time and expense in the separation of the products from the solvent. The vacuum feature of this process involving the solvent in co-operation therewith is also important as the wood or other material is dried and the pores opened to give the solvent greater penetrative access to the products inherent to the wood or carried by the material treated so that the wood is more thoroughly cleaned and under the action of a moderate heat the products are completely eliminated, thus better preparing the wood for after treatment for pulping purposes. It is obvious that where the wood or material treated is subjected to a vacuum or the still in which it is disposed has a vacuum created therein, less heat is required to obtain a perfect elimination than under other conditions or without a vacuum, and hence the wood is less liable to become scorched or discolored, with material advantages in after pulping operations.

40 The variations in practising the steps of the process as hereinbefore described provide for the treatment of various kinds of wood, or wood carrying different products some of which may be more difficult in elimination than others, so that the wood, of whatever nature it may be, will be thoroughly treated and ready for subsequent pulping operations with material advantages from a standpoint of economy and expedition in result.

45 What is claimed is:

1. The process of extracting rosin and other by-products from wood, consisting in disposing a quantity of rosin bearing wood reduced to small pieces in a receptacle, applying a mixture of about one-fifth turpentine and four-fifths deodorized benzin over and about the wood, subjecting the mixture and wood to the action of heat, and drawing off the eliminated rosin, by-products and mixture and separating the several constituents.
2. The process of extracting rosin and other products from wood, consisting in disposing a quantity of wood reduced to small pieces in a closed receptacle, applying

a solvent consisting of refined turpentine and deodorized benzin over and about the wood, said solvent containing about one-fifth turpentine, subjecting the solvent and 5 wood to the action of heat, drawing off the remaining solvent and the by-products as well as the rosin, and separating the rosin and by-products from the solvent and re-using the latter in the treatment of a new 10 charge of wood.

3. The process of extracting rosin and other by-products from wood, consisting in disposing a quantity of wood reduced to small pieces in a receptacle, applying a solvent embodying refined turpentine and deodorized benzin over the wood, said solvent containing about one-fifth turpentine, subjecting the solvent and wood to the action 15 of heat, drawing off the solvent, rosin and other by-products and separating the several constituents, and injecting steam in and through the wood in the receptacle to carry off the solvent and other products remaining in the wood in the form of a vapor and 20 condensing the latter to separate the constituents thereof.

4. The process of extracting rosin and other products from wood, consisting in disposing a quantity of wood reduced to small 30 pieces in a closed receptacle, applying a solvent consisting of refined turpentine and deodorized benzin in suitable proportions over the wood, said solvent containing about one-fifth turpentine, establishing a vacuum 35 in the receptacle, subjecting the solvent and

the wood to the action of heat, and drawing off the solvent and products eliminated thereby and separating the several constituents of the solution.

5. The process of extracting rosin and other products from wood, consisting in disposing a quantity of wood reduced to small pieces in a closed receptacle, applying a solvent consisting of refined turpentine and deodorized benzin in the proportion of 40 about one-fifth turpentine over the wood, externally and internally heating the wood and solvent, and finally drawing off the 45 solution embodying the solvent and products and separating the latter. 50

6. The process of extracting rosin and other products from wood, consisting in disposing a quantity of wood reduced to small pieces in a closed receptacle, admitting a solvent to the receptacle consisting of refined turpentine and deodorized benzin in proper proportions to cover the wood, establishing a vacuum in the receptacle, externally and internally heating the wood and solvent, and finally draining off the 55 solution and products and separating the latter. 60

In testimony whereof I have hereunto set my hand in presence of two subscribing witnesses.
